FIG. 4

234

William J. Bracken, Inventor

C. L. Parker, Attorneys

UNITED STATES PATENT OFFICE.

WILLIAM J. BRACKEN, OF ZION CITY, ILLINOIS.

HOT-AIR-SUPPLY MEANS FOR INTERNAL-COMBUSTION ENGINES.

1,142,871.

Specification of Letters Patent. Patented June 15, 1915.

Application filed August 7, 1914. Serial No. 855,679.

To all whom it may concern:

Be it known that I, WILLIAM J. BRACKEN, a subject of the King of Great Britain, residing at Zion City, in the county of Lake 5 and State of Illinois, have invented certain new and useful Improvements in Hot-Air-Supply Means for Internal-Combustion Engines, of which the following is a specification.

10 My invention relates to apparatus for supplying heated air into the manifold pipe of an internal combustion engine or into the cylinder or cylinders thereof, in the presence of a more or less vaporized hydrocarbon 15 fuel, for the purpose of effecting an intimate mixture of the vaporized hydrocarbon fuel and the heated air, to produce an explosive charge of high efficiency.

An important object of the invention is 20 to provide apparatus of the above mentioned character, which is simple in construction, cheap to manufacture, and may be conveniently adjusted for varying the amounts of heated air to be supplied to the gas or 25 vaporized hydrocarbon fuel, at or before the time that the same enters the cylinder or cylinders of the engine.

A further object of the invention is to 30 provide means of the above mentioned character, formed of few and simple parts which may be readily assembled and separated, rendering it convenient to clean or repair the same.

35 Other objects and advantages of the invention will be apparent during the course of the following description.

In the accompanying drawings forming a part of this specification and in which like numerals are employed to designate like 40 parts throughout the same, Figure 1 is a central longitudinal sectional view through apparatus embodying my invention, Fig. 2 is a horizontal sectional view taken on line 2-2 of Fig. 1, Fig. 3 is a fragmentary side 45 elevation of the lower screw-threaded extension of the relatively stationary shell-member, and, Fig. 4 is a transverse sectional view through a hot air supply casing, associated elements being shown in elevation.

50 In the drawings, wherein for the purpose of illustration is shown a preferred embodiment of the invention, the numeral 5 designates the manifold pipe of an internal combustion engine, preferably provided with an upstanding internally screw-threaded cou-

pling element 6, for a purpose to be described.

My apparatus comprises a preferably cylindrical longitudinally extensible shell or casing 7, embodying relatively movable cup-shaped shell-members 8 and 9, as shown. The shell-member 8 preferably telescopes the shell-member 9, and is relatively stationary while the shell-member 9 is capable of moving longitudinally of the shell-member 8, as is obvious. The lower end of the shell-member 8 is closed by a head or end 10, provided with the outlet port or passage 11, passing through a reduced tubular extension 12, which is externally screw-threaded for engagement with the screw-threads of the coupling member 6, as shown. The upper end of the shell-member 9 is closed by a head or end 12', provided with a reduced tubular screw-threaded extension 13, 75 adapted for connection with an elbow 14, as shown.

Secured to the lower end of the tubular extension 12 is a conical or tapered perforated nozzle 15, extending into the manifold pipe 5 and decreasing in diameter downwardly. This nozzle is formed of foraminous material, preferably wire gauze. The function of providing this tapered nozzle formed of wire gauze, is to spray the hot air into the manifold pipe, in the presence of the more or less vaporized hydrocarbon fuel, whereby an intimate mixture of the vaporized hydrocarbon fuel and the air is obtained. The nozzle 15 is secured to the reduced extension 12 by any suitable means, as by having a portion of the material of this nozzle extending into an annular groove formed upon the exterior of the tubular extension 12 and bound or tied therein by an annulus 16 or the like, as shown.

Formed upon the inner surface of the end or head 10 is a concentrically arranged cage 17, preferably cast integral therewith. This cage is preferably cylindrical and is provided in its side wall with openings 18, to permit of the free passage of the heated air into the port or passage 11. The top of this cage 17 is formed closed and is preferably provided with an upstanding boss 19, having a screw-threaded opening, for receiving the lower screw-threaded end of a valve guide rod 20, to rigidly hold the same in a concentric relation to the shell 7, such rod extending longitudinally of the shell,

as shown. Mounted to reciprocate upon the guide rod 20 is an upwardly seating valve 21, urged upwardly by a compressible and expansible coil spring 22, preferably tapered or conical and increasing in diameter upwardly. This coil spring surrounds the guide rod 20 with its upper large end fitting within and held by a depending annular flange 23 formed upon the valve 21, while the lower small end of the coil spring engages the cage 17 and surrounds the boss 19, to be held thereby against displacement. The valve 21 engages the inner inclined face 24 of the head or end 12', as a seat.

Surrounding the tubular extensions 12 and 13 of the shell-members are apertured preferably triangular plates 25 and 26, preferably provided at their corners with openings 27, for receiving the hooked ends of retractile coil springs 28, preferably three in number. The combined strength of the retractile coil springs 28 is sufficient to compress or overcome the expansible coil spring 22 to place the same under the desired tension, whereby the valve 21 will open upon different degrees of suction within the cylinder or cylinders of the engine.

Means are provided to raise and lower the upper casing-member with relation to the other casing-member, whereby the tension of the springs 28 upon the valve 21 and the corresponding compression of the spring 22 will be reduced, varied, or removed. Such means preferably includes a link 29 secured to the elbow 14 by a member 30. Any suitable means may be employed to move the link 29 longitudinally or up or down, such as a hand operated lever or a foot pedal. As such devices are well known in the arts it is deemed unnecessary to show the same.

The elbow 14 is preferably provided with a cold or fresh air inlet 31, covered by a ball-valve 32, held in place by means of a leaf spring 33 or the like, as shown.

Heated or hot air is supplied into the apparatus through a flexible pipe or conduit 34, connected with a hot air container 35, through the medium of a coupling 36 or the like. This hot air container surrounds a portion of the exhaust pipe 37, as more clearly illustrated in Fig. 4. The opposite ends of this hot air container 35 are preferably closed by rings 38 snugly receiving the exhaust pipe 37. The air is admitted into the container 35 by opening or openings 39, of suitable size, which are covered by spherical perforated or foraminous members 40, preferably formed of wire gauze. This member is held in place by a leaf spring 41 or the like. The function of the members 32 and 40 is to strain the air preventing dust and the like from entering the apparatus.

The operation of the apparatus is as follows:—The engine is started in the usual manner, and when it is desired to supply hot air to the intake manifold or cylinder or cylinders thereof, the casing-member 9 is elevated, the amount of hot air supplied being regulated by the distance that this casing-member is raised. When the engine is running, the suction in the cylinder or cylinders thereof automatically unseats the valve 21, such valve automatically returning to its seat to prevent products of combustion or the like passing into the coupling 14. It is obvious that hot air may be supplied to the cylinder or cylinders, at different degrees of vacuum therein, by raising or lowering the casing-member 9 with the result that the tension of the springs 28 is removed from the valve 21 and spring 22. The hot air passing through the tapered nozzle 15 is sprayed, in the presence of more or less of the vaporized hydrocarbon fuel, thus serving to effect a more thorough vaporization of the same and intimate mixture thereof with the hot air.

While I have shown and described my apparatus as connected with the intake manifold of the engine, it is obvious that the same may be directly mounted upon the cylinder of the engine.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having described the invention, I claim:—

1. In apparatus of the character described, a longitudinally extensible shell, a valve engaging a portion of the shell to control the inlet of air into the same, yielding means to oppose the movement of the valve in one direction, yielding means to automatically contract the longitudinally extensible shell upon a portion thereof being released, and means to extend the shell.

2. In apparatus of the character described, a longitudinally extensible shell provided at one end with an inlet opening, a valve arranged within the shell to engage the same adjacent the opening to close the opening, a spring to urge the valve toward its closed position, yielding means to automatically contract the longitudinally extensible shell upon a portion thereof being released and being stronger than the spring, and means to extend the longitudinally extensible shell.

3. In apparatus of the character described, a plurality of freely relatively reciprocatory telescoping shell-members, a valve arranged within one shell-member to engage the end thereof to control the pas-

sage of air into the same, a spring to move the valve into engagement with the end of the shell-member, and means to reciprocate one shell-member with relation to the other 5 without turning the same upon its longitudinal axis.

4. In apparatus of the character described, a plurality of telescoping shell-members, a movable valve arranged within 10 one shell-member to control the passage of air into the same, a spring engaging the valve to oppose its movement in one direction, a retractile coil spring extending longitudinally of the telescoping shell members 15 and connecting the same to automatically move one shell member inwardly upon the same being released, and means to move such shell member outwardly in opposition to the spring.
- 20 5. In apparatus of the character described, a shell, a member movable longitudinally with relation to the shell and serving to close one end thereof and having an inlet opening, a valve adapted to engage 25 the member and close the inlet opening, a spring to move the valve into engagement with the member, a spring to automatically move the member longitudinally in one direction upon the same being released, and 30 separate means to move the member longitudinally in an opposite direction in opposition to the second named spring.
6. In apparatus of the character described, a relatively stationary shell-member having one end open and the opposite end provided with a head having an opening and an apertured cage, a co-acting shell-member having one end provided with an 35

inlet opening and its opposite end slidably engaging the relatively stationary shell-member, a valve rod secured to the apertured cage and extending longitudinally within the shell-members, a valve slidably mounted upon the valve rod and engaging the apertured end of the co-acting shell-member, a coil spring surrounding the valve rod and engaging the valve, retractile coil springs connecting the shell-members, and means to move the co-acting shell-member 40 with relation to the relatively stationary shell-member and in opposition to the retractile coil springs.

7. In apparatus of the character described, a relatively stationary shell-member having one end open and the opposite end 45 provided with a head having an outlet opening and an apertured cage, a co-acting shell-member having one end provided with an inlet opening and its opposite end slidably engaging the relatively stationary shell-member, a valve rod secured to the apertured cage and extending longitudinally 50 within the shell-members, a valve slidably mounted upon the valve rod to engage the apertured end of the co-acting shell-member, plates connected with the opposite ends 55 of the shell-members, retractile coil springs connecting the plates, and means to move the co-acting shell-member in a direction in opposition to the retractile coil springs.

In testimony whereof I affix my signature in presence of two witness.

WILLIAM J. BRACKEN.
